UNITED STATES PATENT OFFICE

AUGUST BÖTTNER, OF ELTMANNSHAUSEN, GERMANY

WINDOW PANE

Application filed September 12, 1928, Serial No. 305,550, and in Germany January 23, 1928.

This invention relates to a window pane composed of two spaced glass plates, each of which is provided with a groove in each of its four rims, the two grooves being located opposite one another and containing a packing strip. Besides, a non-return valve is provided through which the air enclosed in the space between said glass plates can be sucked away and by which said space can be kept exhausted. A window pane of this improved kind presents the advantages over the known windows (single, as well as double ones) that it is more durable and affords better protection from heat and coldness; especially if the space between the two glass plates has been exhausted, as is to be the rule. The improved window pane can be used not only for the windows of houses and other abodes, but also for industrial edifices, cooling houses, horticultural buildings, and the like.

The invention is illustrated diagrammatically and by way of example on the accompanying drawing, on which Figure 1 is a front-view of a window pane designed according to this invention, and Figure 2 is a vertical transverse section through the same.

On the drawing, *a* and *b* denote the two glass plates, which are provided with grooves *a*² and *b*² in each of their rims *a*¹ and *b*¹. The glass plates are spaced, as shown in Fig. 2, and their proper distance is maintained by packing strips *c*, whereby a hollow space *d* is formed and maintained between them.

This space can be exhausted through a non-return valve which then keeps said space continually in exhausted state.

I claim:

40 A window pane, comprising two spaced glass plates having each a groove in each rim and being so arranged relatively to one another that the grooves of the two plates lie opposite one another, and packing strips 45 located in said grooves.

In testimony whereof I affix my signature.

AUGUST BÖTTNER.
